Charles S. Goodwin.

UNITED STATES PATENT OFFICE.

JOHN A. FRAIZE, OF FRAMINGHAM, MASSACHUSETTS.

SPRING-BED.

1,239,171.

Specification of Letters Patent. Patented Sept. 4, 1917.

Application filed June 21, 1916. Serial No. 105,046.

To all whom it may concern:

Be it known that I, JOHN A. FRAIZE, a citizen of the United States, residing at Framingham, in the county of Middlesex and State of Massachusetts, have invented new and useful Improvements in Spring-Beds, of which the following is a specification.

This invention relates to an improved 10 spring bed of that character which is collapsible, that is, where one-half of the spring bed can be swung over upon the other half, thus making the bed substantially one-half of its full width so that the same can 15 be easily stored or transported from one place to another, and especially in cases where it is desired to carry the spring bed up or down stairs it can be folded so as to 20 reduce the liability of defacing the walls of the building while being moved.

It is the principal object of this invention to eliminate a central longitudinally extending rail while at the same time providing a collapsible spring bed which is perfectly 25 strong and supports the spring in an efficient manner, thus rendering the spring bed more comfortable and convenient. Also it will be noted that when the spring bed is in its folded position, the central longitudinally 30 extending rail being absent, it is much easier to reach beneath the spring bed to sweep the floor.

The invention consists in the combination 35 and arrangement of parts set forth in the following specification and particularly pointed out in the claim thereof.

Referring to the drawings:

Figure 1 is a plan view of a spring bed 40 constructed in accordance with my invention and illustrated as resting upon a bedstead frame, the same being broken away to save space in the drawings.

Fig. 2 is an end elevation of the spring bed showing the same resting upon the 45 frame of a bedstead.

Fig. 3 is a sectional elevation similar to Fig. 2 taken on line 3—3 of Fig. 1.

Fig. 4 is a sectional elevation taken on line 3—3 of Fig. 1 showing the bed spring 50 in its folded position, the bedstead frame being broken away to save space in the drawings.

Like numerals refer to like parts throughout the several views of the drawings.

55 In the drawings 5 and 6 are the side rails of a bedstead. 7 and 8 are the head and

foot rails, respectively, of said bedstead. 9 and 10 are two sections of my improved 60 spring bed. The section 9 consists of a head rail 11 and a foot rail 12 extending transversely of the section 9 and joined together by a longitudinal rail 13 which is fastened to the head rail 9 and foot rail 12 by brackets 14. The brackets 14 have lateral projections 15 thereon which are adapted to 65 bear upon the upper edge of the side rail 6 of the bedstead when the bed spring is in position to be used. It will be noted that the longitudinal rail 13 is adjacent to the outer edge of the section 9. 70

The section 10 consists of a head rail 16 and a foot rail 17 which are joined together by a longitudinally extending rail 18, the rail 18 being fastened to the head rail 16 and the foot rail 17 by brackets 19. The longitudinal rail 18 is adjacent to the outer edge 75 of the section 10. Said brackets 19 have lateral projections or ears 31 thereon which rest upon the side rail 5 of the bedstead when the spring is in its operative position. 80

The head rails 11 and 16 and the foot rails 12 and 17 are hinged together by means of two pairs of links 20 and 21. The inner links 21 terminate at their opposite ends in angular lugs 22 which constitute stops when 85 the two sections of the bed spring are folded together, as illustrated in Fig. 4, these stops abutting against the horizontal webs of the angle rails 11 and 16, 12 and 17, respectively. 90

To support the inner edges of the sections 9 and 10 a T-shaped bracket 23 is fastened to the head rail 11 and another T-shaped bracket 24 is fastened to the foot rail 12 of the section 9. It will be noted that the horizontal flanges 25 of the brackets 23 and 24 extend under and form a support for the inner ends of the head rail 16 and the foot rail 17 of the section 10 when said section 10 is in a horizontal extended position. When the section 10 is folded over on the section 9, however, the vertical flanges of the head rail 11 and the foot rail 12 form a support for the vertical flanges of the head rail 16 and foot rail 17 of the section 10. 95

The bed spring 26 is fastened to the head and foot rails of the two sections 9 and 10. Diagonal braces 27 and 28 extend from the longitudinal rail 13 to the head rail 11 and to the foot rail 12, respectively, of the section 9, and diagonal braces 29 and 30 extend from the longitudinal rail 18 to the head rail 16 100

110

and the foot rail 17 of the section 10 for the purpose of strengthening said parts and holding them firmly in proper relation to each other.

5 The bed spring hereinbefore specifically described is operated as follows: When the parts are in the position illustrated in Figs. 2 and 3, the bed spring is supported, as a whole, upon the frame of the bedstead, the 10 laterally extending projections or ears 15 upon the brackets 14 and the laterally projecting ears 31 upon the brackets 19 resting, respectively, upon the side rails 6 and 5 of the bedstead, while the brackets 23 and 24 15 rest upon the head rail 7 and the foot rail 8 of said bedstead. When it is desired to fold the bed spring the section 10 is turned over upon the section 9, the two pairs of links 20 and 21 acting as hinges to enable 20 this to be easily done. During this turning over of the section 10 upon the section 9 the lugs 22 upon the ends of the links 21 act as stops to regulate the position which 25 the head and foot rails of the section 10 assume relatively to the head and foot rails of the section 9. When the section 10 has

been completely folded over upon the section 9, as illustrated in Fig. 4, said lugs 22 come into contact with the horizontal flanges of the head and foot rails of the sections 9 and 10 as illustrated in Fig. 4.

I claim:

A spring bed having, in combination, two sections hinged together, each section comprising a head rail and a foot rail extending 35 transversely thereof and joined together only by a longitudinal rail adjacent its outer edge, a bed spring fastened to said sections, a T-shaped bracket fastened to the inner ends of the head and foot rails of one of said 40 sections and projecting beneath the head and foot rails of the other of said sections, said brackets being adapted to rest upon the head and foot rails, respectively, of a bedstead and forming supports for said sections. 45

In testimony whereof I have hereunto set my hand in presence of two subscribing witnesses.

JOHN A. FRAIZE.

Witnesses:

CHARLES S. GOODING,
SYDNEY E. TAFT.
